SIGN FOR MERCHANDISING DISPLAY STANDS AND THE LIKE

Thaddeus I. Kingsford, Atlanta, Ga., assignor to Scripto, Inc., a corporation of Georgia

Filed Feb. 5, 1963, Ser. No. 73,457

Term of patent 14 years

(Cl. D1—12)

Fig. 1

Fig. 2

Fig. 3

Fig. 4

Fig. 5

FIG. 1 is a front elevational view of the sign embodying my new design;

FIG. 2 is a side elevational view;

FIG. 3 is a vertical cross sectional view thereof;

FIG. 4 is a top plan view; and,

FIG. 5 is a rear elevational view.

The letters shown in broken lines in FIGS. 1 and 3 and the fragmentary broken line representation of a stand in FIGS. 1, 2, 3 and 5 are for purpose of illustration.

I claim:

The ornamental design for a sign for merchandising display stands and the like, as shown and described.
